CLAIM

The ornamental design for an inhaler container for a medical aerosol, as shown and described.

DESCRIPTION

FIG. 1 is a perspective view of an inhaler container for a medical aerosol showing my new design;

FIG. 2 is an exploded perspective view thereof;

FIG. 3 is a side elevational view thereof;

FIG. 4 is a top plan view thereof;

FIG. 5 is a bottom plan view thereof;

FIG. 6 is a perspective view thereof in storage position wherein the top is inverted and placed inside the bottom of the container position.
